UNITED STATES PATENT OFFICE

133,029

DESIGN FOR A RICE DRIER

George L. Hurst, San Francisco, Calif.

Application April 20, 1942, Serial No. 106,636

Term of patent 7 years

To all whom it may concern:

Be it known that I, George L. Hurst, a citizen of the United States, residing in the city and county of San Francisco and State of California, have invented a new, original, and ornamental Design for a Rice Drier, of which the following is a specification, reference being had to the accompanying drawing, forming part thereof.

Fig. 1 is an elevational view of a rice drier showing my new design.

Fig. 2 is a plan view of the rice drier of Fig. 1.

The finely spaced cross lines shown only on part of the cylindrical portions between the vertical and horizontal rails, represent screen material which extends throughout the several individual areas, and the opposite side of the drier is substantially like the side shown in Fig. 1.

I claim:

The ornamental design for a rice drier, as shown and described.

GEORGE L. HURST.
